UNITED STATES PATENT OFFICE.

MOSE G. LAMB, OF SIKESTON, MISSOURI, ASSIGNOR TO JOHN W. ADAMS, OF SIKESTON, MISSOURI.

BORING-MACHINE.

1,204,576.

Specification of Letters Patent. Patented Nov. 14, 1916.

Application filed December 30, 1915. Serial No. 69,427.

To all whom it may concern:

Be it known that I, MOSE G. LAMB, a citizen of the United States, residing at Sikeston, in the county of Scott and State of 5 Missouri, have invented certain new and useful Improvements in Boring-Machines, of which the following is a specification, reference being had to the accompanying drawings.

10 This invention relates to certain improvements in boring machines and has relation more particularly to a device of this general character especially designed and adapted for use for boring cylinders or the like; and 15 it is an object of the invention to provide a machine of this general character having novel and improved means whereby it may be applied into operative position with convenience and facility and maintained in 20 such position by the cylinder with which it is adapted to coat.

Furthermore, it is an object of the invention to provide a machine of this general character having novel and improved means 25 whereby the direction of travel of the boring bar may be effectively and conveniently controlled.

It is also an object of the invention to provide a novel and improved machine of this 30 general character whereby the guides for a cross head may be bored simultaneously with the boring of a cylinder.

The invention consists in the details of 35 construction and in the combination and arrangement of the several parts of my improved boring machine whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the 45 better understood, I will now proceed to describe the same with reference to the accompanying drawings, wherein—

Figure 1 is a sectional view illustrating a 50 boring machine constructed in accordance with an embodiment of my invention and in applied position; Fig. 2 is a view in elevation of the outer face of my improved boring machine; Fig. 3 is a transverse sectional view taken through a cylinder showing a cutter head constructed in accordance with

an embodiment of my invention coacting therewith; Fig. 4 is a transverse sectional view taken through the reversing or feeding mechanism as herein included; Fig. 5 is a longitudinal sectional view taken through 60 the reversing or feeding mechanism, with the boring bar shown in fragment and in elevation and an adjacent portion of the frame in section; Fig. 6 is a fragmentary view, partly in elevation and partly in section, illustrating certain details of construction as herein embodied; Fig. 7 is a fragmentary view in section of a slightly modified form of my invention especially as relates to the centering of the boring bar; Fig. 70 75 Fig. 8 is a detail view partly in elevation and partly in section illustrating a further means for centering the boring bar; and Fig. 9 is a sectional view taken substantially on the line 9—9 of Fig. 8.

As disclosed in the accompanying drawings, C denotes a cylinder of conventional type adapted for use in connection with a rectilinear piston and G denotes conventional guides for a cross head as generally 80 included in an engine of a reciprocating type.

When it is desired to bore the cylinder C, the outer cylinder head and piston are removed and the frame F of my improved 85 boring machine is secured directly to the open end of the cylinder.

The frame F, as herein embodied, comprises the overlying plates 1 and 2 maintained in fixed spaced relation by the clamping bolts 3 and the interposed sleeves 4 embracing said bolts. The plates 1 and 2 are provided with the aligned openings 5 arranged at the axial center of the cylinder C when the frame is in applied position and 90 disposed through said openings 5 is the boring bar B, said boring bar being of a length materially in excess of the length of the cylinder and directed through the stuffing box S of the cylinder C whereby it will 95 be perceived that the boring bar B is effectively maintained in operative position through the cylinder C at the axial center thereof as it is to be noted that the stuffing box gland 6 coats with the boring bar B. 100 105

The outer end portion of the boring bar B is provided with a longitudinally disposed key-way 7 to receive the key 8 which serves to lock the gear wheel 9 to the boring bar B so as to cause the gear and the bar to 110

rotate in unison but permits an independent longitudinal movement in either direction of the bar B.

The gear 9 is positioned between the plates 1 and 2 and is in mesh with the pinion 10 affixed to the shaft 11 rotatably supported by the plates 1 and 2 and extending above the upper plate 1 and said shaft 11 is operatively engaged through the medium of the gear train 12 with the shaft 14 adapted to be rotated in any suitable manner, but herein disclosed as provided with a pulley 15 whereby the shaft may be coupled to a source of power.

15. Adjustably mounted upon the boring bar B is the knife head 16, herein disclosed as being provided at its axial center with an opening 17 through which the boring bar B is disposed and said opening 17 is defined by 20 an annular flange 18 through which the clamping bolts 19 are disposed for engagement with the boring bar B whereby it will be perceived that the knife head 16 may be effectively clamped at a predetermined point 25 longitudinally of the cutter bar B.

At opposite sides of its axial center the knife head 16 is provided with the loops 20 through which the knives or cutters 21 are directed, said knives being maintained in 30 predetermined adjustment through the medium of the clamping screws 22 threaded through the loops 20 and engaging the knives or cutters, said knives being so adjusted as to effectively engage the inner wall 35 of the cylinder 2 so as to properly bore the same. The cutter head is provided at a point in alignment with each set of loops 2 with a lug 23 through which is disposed the set screw 24 engaging the inner end of a 40 knife or cutter 21 so that the same may be readily and effectively adjusted in an outward direction.

If desired, the boring bar B may be of such a length as to extend beyond the guides 45 G for the cross head and in which event the bearing cap 25 is detachably engaged with the guides G through the medium of the clamping screws 26, said bearing cap 25 serving as an additional support for the 50 boring bar B. The portion of the boring bar B interposed between the guides G has secured thereto the knife head 27 of a construction preferably similar to the head 16 and said head 27 has coacting therewith the 55 knives or cutters 28 in a manner similar to that as has hereinbefore been set forth relative to the knives or cutters 21.

The upper plate 1 has secured thereto a cap 29 provided with an annular flange concentric to the opening in said plate 1 and to which is non-rotatably affixed the cylinder 30 of predetermined dimensions having its upper extremity provided with the exterior threads 31 with which is engaged the annular flange 32 depending from the top cap 33.

The caps 29 and 33 are provided with the equidistantly spaced radial slots 34 preferably four in number and in which are arranged the extremities of the shafts 35 having mounted thereon intermediate their 70 lengths the rollers 36 adapted to engage the periphery of the boring bar B.

It has been fully demonstrated in practice that upon imparting axial rotation to the upper cap 33 in the requisite direction, 75 the resultant inclination of the rollers 36 will so contact with the boring bar B as to cause the same to feed or travel inwardly or outwardly relative to the cylinder C.

As herein disclosed, I affix to the upper 80 cap 33 the operating lever or handle 37 provided with a spring latch 38 of conventional construction adapted to coact with the spaced perforations produced in the upper portion of the cylinder 30, whereby the rollers 85 will be locked in their various adjustments.

In order to impose the requisite tension upon the shafts 35 so as to cause the rollers 36 to effectively engage the boring bar B, I 90 dispose through the cylinder 30 at points above and below the rollers 35 the set screws 39 having their inner extremities provided with the springs 40 bearing against the shafts 35 whereby it will be perceived that 95 equal pressure is imparted to the rollers 36 irrespective of the angle of adjustment of the shafts 35.

I have found it of particular advantage and as especially illustrated in detail in 100 Fig. 7, to provide an independent cone bearing 41 through which the boring bar B may be disposed and it is to be noted that said bearing 41 owing to its formation coacts with the stuffing box 42 in such a manner as 105 to bring the boring bar B to a true center at the adjacent end of the cylinder C. I also find it of advantage to provide at the end of the cylinder adjacent the frame F additional means whereby the proper centering 110 of the boring bar B may be assured. As illustrated in detail in Figs. 8 and 9, I employ a conventional centering device including the dogs 43 coacting with the cylinder C in a conventional manner and properly 115 adjustable through the medium of the screws 44, said dogs 43 and screws 44 being carried by the head 45 which is preferably in the form of a spider comprising four arms 46.

From the foregoing description, it is 120 thought to be obvious that a boring machine constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the scope of the claims 125 130

and for this reason I do not wish to be understood as limiting myself to the precise arrangement and formation of the several parts herein shown in carrying out my invention in practice except as required by the scope of the appended claims.

I claim:

1. A boring machine for cylinders and the like comprising a frame adapted to be secured to the cylinder, a boring bar disposed through the frame and mounted for axial rotation and for endwise movement, cutting means carried by the bar, means for rotating the bar, rollers mounted for contact with the bar, and means for inclining the axes of the rollers relative to the bar whereby the longitudinal movement of the bar may be controlled.

2. A boring machine including a boring bar arranged for axial rotation and endwise movement, a cylinder surrounding the boring bar and concentric thereto, heads for the opposite ends of the cylinders, one of said heads being capable of rotative movement, each of said heads being provided with slots, shafts mounted in said slots, rollers carried by the shafts engageable with the bar, and means for imparting movement to the rotative head for inclining the axes of the rollers relative to the bar whereby the longitudinal movement of the bar may be controlled.

3. A boring machine including a boring bar arranged for axial rotation and endwise

movement, a cylinder surrounding the boring bar and concentric thereto, heads for the opposite ends of the cylinders, one of said heads being capable of rotative movement, each of said heads being provided with slots, shafts mounted in said slots, rollers carried by the shafts engageable with the bar, means for imparting movement to the rotative head for inclining the axes of the rollers relative to the bar whereby the longitudinal movement of the bar may be controlled, and means for locking the rotative head against movement.

4. A boring machine including a boring bar arranged for axial rotation and endwise movement, a cylinder surrounding the boring bar and concentric thereto, heads for the opposite ends of the cylinders, one of said heads being capable of rotative movement, each of said heads being provided with slots, shafts mounted in said slots, rollers carried by the shafts engageable with the bar, means for imparting movement to the rotative head for inclining the axes of the rollers relative to the bar whereby the longitudinal movement of the bar may be controlled, and means for imposing tension on the shafts to urge the same toward the boring bar.

In testimony whereof I hereunto affix my signature in the presence of two witnesses.

MOSE G. LAMB.
